Conn., a corporation of New Jersey

Application June 26, 1941, Serial No. 399,773

10 Claims. (CL 229—7)

This invention relates to containers having at least two parts telescopically related to each other and articulatively interconnected in such manner as to facilitate discharge of contents.

Within the scope of the invention, the two parts may be merely slidably relative to each other for enlarging the capacity of the container and for forming an opening for discharge of contents, or may be removable, one from the other, to an extent limited only by the length of the articulative interconnecting means. Instances of removable telescopic covers or caps which are held captive to the container proper come within the latter definition.

The invention is applicable to a variety of types of containers manufactured from various kinds of material, but is especially significant in its application to folding boxes formed from cut and scored blanks of sheet paper-board material by the use of standard automatic machinery.

A primary object of the invention is the provision of a container having at least two parts which telescope relative to each other to facilitate discharge of contents, and which are interconnected by articulative linkage in such manner that the articulative linkage will be concealed when the two parts are in mutual telescopic relationship.

Another object is as above, but with the provision that the articulative linkage will be entirely free and clear of the zone of telescopic engagement of the two parts, so as not to be interjected between normally contiguous and slidably related surfaces during telescopic extension or retraction of the two parts relative to each other.

Another object is as above, but with the provision that the articulative linkage material will not interfere with nor obstruct the normal containing space of the container.

Another object is as above, but with the provision that the two parts of the container, after mutual separation of the parts from their telescopic relationship, as in the case of a so-called "captive cap," may be guided into renewed telescopic relationship relative to each other with a minimum of inconvenience and effort.

A further object is the accomplishment of any one or all of the above objects by a simple and effective construction capable of large scale production on existing types of automatic machinery.

An outstanding feature of the invention, in the attainment of the foregoing objects, resides in the manner of securing of the articulative

linkage to that one container part which fits or telescopes over the other container part, and which is, therefore, termed the "outer" container part. According to the invention such securing is made at the inside of the closed end of said one container part, i. e., the outer container part, such closed end being in most instances the top wall or panel of the container.

Another important feature resides in the nature of the articulative linkage. According to the invention, the articulative portion is preferably of panel formation having a plurality of mutually parallel transverse lines of fold extending thereacross. The lines of fold are preferably such as divide the articulative portion into several substantially similar panel linkage sections which fold together bellows-wise when the two parts of the container are telescopically retracted relative to each other.

Further objects and features of the invention will be apparent from the following detailed description of specific embodiments illustrated in the accompanying drawings.

In the drawings:

Fig. 1 represents a perspective view, taken from the front, of a folding box representing one embodiment of the invention provided with a telescopically movable part having a pouring discharge aperture therein;

Fig. 2, a view corresponding to that of Fig. 1, but illustrating the box in extended condition with the pouring aperture completely opened for discharge of contents, hidden elements being revealed by dotted lines;

Fig. 3, a view similar to that of Fig. 2, but showing the box actually discharging contents through the pouring aperture;

Fig. 4, an enlarged fragmentary view in vertical section taken on the line 4—4 of Fig. 1;

Fig. 5, a view corresponding to that of Fig. 4, but taken on the line 5—5 of Fig. 2;

Fig. 6, a view similar to those of Figs. 4 and 5, but taken on the line 6—6 of Fig. 1;

Fig. 7, a plan view of the inside face of the cut and scored blank used in forming the containing part, the articulative linkage, and portions for completing the telescopically movable part of the folding box illustrated in the foregoing figures;

Fig. 13, a plan view of the inside face of the cut and scored blank used to form the telescopically movable cover part of the embodiment of Fig. 9;

Fig. 14, a fragmentary view illustrating the important upper portion of the cut and scored blank used to form the containing part and articulative linkage of the embodiment of Figs. 9 and 10;

Fig. 15, a view corresponding to those of Figs. 1 and 9, but illustrating a still further embodiment of a type similar to those shown in Figs. 1 and 9;

Fig. 16, a view corresponding to that of Fig. 10, but fragmentary in character and illustrating the embodiment of Fig. 15;

Fig. 17, an enlarged fragmentary vertical section taken on the line 17—17 of Fig. 16;

Fig. 18, a plan view of the cut and scored blank used to form the telescopically movable cover part of the embodiment of Fig. 15;

Fig. 19, a view corresponding to that of Fig. 18, but illustrating the blank used to form the containing part and the articulative linkage of the same embodiment;

Fig. 20, a view corresponding to those of Figs. 1, 9 and 15, but illustrating another type of container pursuant to the invention in the form of a folding box having a removable, so-called "captive cap";

Fig. 21, a view similar to that of Fig. 20, but fragmentary in character and illustrating the removable cap or cover part in open position;

Fig. 22, an enlarged fragmentary view in vertical section taken on the line 22—22 of Fig. 21;

Fig. 23, a view corresponding to that of Fig. 22, but illustrating the cover part in closed position;

Fig. 24, a view somewhat similar to that of Fig. 21, but illustrating the containing part and articulative linkage portion in front elevation, and the removable cap or cover in bottom plan;

Fig. 25, a plan view illustrating the inside face of the cut and scored blank used to form the removable cap or cover part of the embodiment of Fig. 20;

Fig. 26, a view corresponding to that of Fig. 25, but illustrating the blank used to form the containing part and the articulative linkage of the same embodiment;

Fig. 27, a view corresponding to that of Fig. 22, but illustrating a different manner of securing the articulative linkage portion to the removable cap or cover part;

Fig. 28, a plan view of the cut and scored blank used to form the removable cap or cover part of the embodiment of Fig. 27;

Fig. 29, a plan view illustrating a fragment of the articulative linkage portion of the blank which is used to form the containing part as well as the articulative linkage portion of the embodiment of Fig. 27; and

Fig. 30, a view similar to that of Fig. 27, but illustrating still another manner of attaching

the articulative linkage portion to the removable cap or cover part.

Practical exemplification of the novel concepts of the invention are illustrated and described specifically with respect to various types of folding boxes formed of paper-board material. Utilization of the novel concepts in containers other than those falling within the category of folding boxes may be carried out by those skilled in the art from the structural characteristics and features here set forth.

The type of folding box in which one part is a cover secured in telescopic relationship over the mouth of a containing part, or box proper, is illustrated in Figs. 1 through 8. The cover, or "outer," part is connected to the box proper by articulative linkage which allows only limited telescopic sliding movement of the cover part relative to the box proper. The cover part here is not adapted for separation or removal from the box proper as it is in certain other embodiments of the invention.

The box proper 10 is formed from the cut and scored blank of Fig. 7, preferably by the use of standard automatic machinery. The cover part 11 is formed from the blank of Fig. 8 in cooperation with certain portions of the blank of Fig. 7.

The blank of Fig. 7 is novel only so far as the upper portion thereof is concerned. Its lower portion, adapted to form the bottom closure of the box proper, may be provided in a variety of conventional styles, the one illustrated being adapted to form a conventional glued type closure.

The blank of Fig. 7 comprises a front wall panel 12, a rear wall panel 13, side wall panels 14 and 15, respectively, and a conventional glue lap 16, all interconnected in edge-to-edge serial alignment and individually defined by suitable score lines. Bottom closure flaps 17 and 18 extend from the lower ends of the front and rear wall panels 12 and 13, respectively, and bottom closure supporting flaps 19 and 20 extend from the lower ends of the side wall panels 14 and 15, respectively. The bottom closure flaps are adapted to be glued together in forming the conventional bottom closure indicated at 21, Figs. 1, 2, and 3. Extending from the upper ends of the front and rear wall panels 12 and 13, respectively, are the respective articulative linkage portions indicated generally 22 and 23. The respective linkage portions 22 and 23 are, in this instance, identical in formation, and include respective sets of linkage sections comprising the linkage panels 22a, 22b, 22c, and 23a, 23b, and 23c, respectively. In the present embodiment, the linkage panels 22a and 23a form the top closure of the box, and cooperate with the blank of Fig. 8 in forming the cover part 11. The respective sets of linkage sections 22b, 22c and 23b, 23c fold bellows-wise within the cover part 11, and provide for limited up and down telescopic sliding movement of the cover part 11 relative to the containing part, or box proper, 10.

The blank of Fig. 8 comprises front and rear wall panels 24 and 25, respectively, side wall panels 26 and 27, respectively, and a conventional glue lap 28, all interconnected in edge-to-edge serial alignment, and individually defined by suitable score lines. Closure supporting flaps 29 and 30 extend from the upper ends of side wall panels 26 and 27, respectively, and friction-sealing flaps 31 and 32 extend from the lower ends thereof. Arcuate indentations 33 and 34 are preferably supplied substantially centrally of the upper mar-

ginal edges of the front and rear wall panels 24 and 25, respectively, for a purpose hereinafter explained. To provide a pouring aperture for the discharge of contents from the box, an opening 35, conveniently of substantially diamond configuration, as illustrated, is formed in one of the side wall panels, here the panel 27.

The blanks of Figs. 7 and 8 are folded on their respective score lines and glued, in conventional manner. The bottom closure 21 may be closed and sealed either before or after the part formed by the blank of Fig. 8 is installed in place on the part formed by the blank of Fig. 7. Ordinarily, however, it will be closed and sealed prior to the filling of the box, such filling being accomplished immediately prior to installing the part formed by the blank of Fig. 8 in place.

In forming the top closure 36 of the box, and in articulatively linking the cover part 11 to the containing part, or box proper, 10, the part formed by the blank of Fig. 8 is slid over the upper portion of the part formed by the blank of Fig. 7, care being taken to see that the friction-sealing flaps 31 and 32 are folded upwardly against the inside face of the side wall panels 26 and 27, respectively, see Figs. 4, 5, and 6. The linkage portions 22 and 23, as folded on the several mutually parallel score lines between the respective panel sections 22b, 22c and 23b, 23c, are pressed down to form the bellows 37 and 38, respectively, see Fig. 4. The closure supporting flaps 29 and 30, of the part formed by the blank of Fig. 8, are then folded down upon the bellows 37 and 38, as is illustrated in Fig. 4, and the top closure flaps 22a and 23a folded down thereover and secured into place, preferably by gluing. In this manner, the closure supporting flaps 29 and 30 are inter-leaved between the two bellows 37 and 38 and the top closure flaps 22a and 23a, and the part formed by the blank of Fig. 8 is thus locked to the part formed by the blank of Fig. 7. The cover part 11 is completely formed with articulative connection to the container part 10 through the bellows 37 and 38.

It can be seen that the articulative linkage provided by the bellows 37 and 38 is secured at the under-side of the top wall of the cover part 11, and, when the cover part 11 is in completely telescoped position with respect to the containing part, or box proper, 10, that the articulative linkage fits closely against the under-side of the said top wall, without in any way impeding the telescopic sliding movement of the two parts relative to each other, nor obstructing or reducing the containing capacity of the box.

The marginal indentations 33 and 34 of the cover part 11 facilitates the grasping of such cover part in extending the container to the position shown in Figs. 2, 3, and 5. In such extended position, the volume of the container is enlarged so that additional space is provided for facilitating initial movement of the contents toward the pouring aperture 35, see Fig. 3. After discharge of a desired quantity of the contents of the box, the cover part 11 may be telescoped into closed position over the upper portion of the containing part, or box proper, 10, thus closing the pouring aperture 35. The friction-sealing flaps 31 and 32 provide effective seals against undesired sifting of contents from the box while closed and against the admission of vermin.

As illustrated in Fig. 8a, the blank of Fig. 8 might be provided with means adapted to form a pouring aperture at some future time, rather than with the actual aperture 35. Such means may

be a pull-out flap 39 having a suitable polygonal configuration, such as is illustrated, outlined in its major part by deep perforations and in a minor part, as at 39a, by a score line which becomes a hinge for the pull-out flap when the line of perforations is cut through for discharging the contents of the box. The vertical length of such flap 39 is desirably such as to extend below the top edge of the box proper when the same is in fully extended position so that in reseating the flap to reclose the pouring aperture, it will have a supporting surface to prevent its being pressed through the aperture.

In instances of packaging loose, fluffy, or flaky substances in such a box, the box may be assembled and set up for filling with the two telescopically related parts in extended relationship. After filling the thus set up box through the bottom, and after sealing the bottom closure, as previously described, the filled box may be placed on a vibrating rack to settle the contents, whereafter, the telescopically related parts of the box may be compressed together to remedy what would otherwise constitute a state of slack-packing.

The embodiment illustrated in Figs. 9 through 14 is similar in many respects to that aforementioned. The cover part 40 is connected to the containing part, or box proper, 41 by articulative linkage which allows only limited movement of such cover part relative to such box proper. In this embodiment, however, the cover part is separable and removable from the containing part, within limits determined by the length of the connecting linkage. Such connecting linkage serves to facilitate placement of the cover part over the mouth of the box proper by guiding it thereto. Because of the nature of the relationship between the cover part and the box proper, in extended or open position, apertures are formed between the two parts for the convenient discharge of contents from the box.

The box proper 41 is formed from the cut and scored blank of Fig. 14 in a manner similar to that aforementioned with respect to the box proper 10. The lower portion of the blank of Fig. 14, indicated in the drawings as broken away, is identical with the lower portion of the blank of Fig. 7, and is adapted to form a glued type bottom closure 42 which is identical with the aforementioned bottom closure 41. The blank otherwise comprises front and rear wall panels 43 and 44, respectively, side wall panels 45 and 46, respectively, and a conventional glue lap 47, all interconnected in edge-to-edge serial alignment, and individually defined by suitable score lines, as is the case in the blank of Fig. 7. Extending from the upper ends of the front and rear wall panels 43 and 44, respectively, are respective articulative linkage portions indicated generally 47 and 48. These linkage portions are mutually identical in formation, and include respective sets of linkage panel sections comprising the panel sections 47a, 47b, 47c and the panel sections 48a, 48b, 48c, respectively, defined by mutually parallel score lines. The panel sections 47b, 47c and the panel sections 48b, 48c fold bellows-wise within the cover part 40, while the panel sections 47a and 48a are respectively secured to the inside surface of the top wall of the cover part 40, as by gluing. Extending from the upper ends of side wall panels 45 and 46, are friction-sealing flaps 49 and 50, respectively. These flaps correspond in function to the friction-sealing tabs 31,

32 of the blank of Fig. 8, as will be explained more fully hereinafter.

The cover part 40 is formed in entirety from the cut and scored blank of Fig. 13. Such blank comprises a substantially centrally located top wall panel 55, from the edges of which extend other wall panel sections, including the front wall forming panel sections 56 and 57, and the thereto oppositely extending rear wall forming panel sections 58 and 59. Such other wall panel sections also include the side wall forming panel sections 60 and 61, and the thereto oppositely extending side wall forming panel sections 62 and 63. For tying the several lateral walls together, interleaving corner flaps 64 and 65 extend from opposite ends of the panel section 58, and similar flaps 66 and 67 extend from opposite ends of panel section 56. Such inter-leaving corner flaps may be reduced in width by edge cuts, as at 68, to compensate for the thickness of the sheet material.

The two parts of the box are formed independently of each other. The blank of Fig. 13 is folded and glued in conventional manner to form the cover part 40, while the blank of Fig. 14 is also folded and glued in conventional manner to form the box proper 41. In the latter instance, the friction-sealing flaps 49 and 50 are folded downwardly, as indicated in Fig. 10, and the linkage panel sections 47b, 47c and 48b, 48c of the respective linkage portions 47 and 48 are folded upon themselves to form the bellows 69 and 70, respectively, Fig. 10. The linkage sections 47a and 48a are folded as indicated in Fig. 12, and are secured, preferably by gluing, to the inside face of the top wall panel 55 of the cover part 40.

The cover part 40 is now permanently secured to the box proper 41, and may be telescoped into and from its closing position over the mouth of the box proper 41 as desired. When the cover part is removed from the box proper, as illustrated in Fig. 10, openings, as at 71, are formed at both sides of the box between the cover part and the box proper. Such openings form pouring apertures, corresponding to the pouring aperture 35 in the aforescribed embodiment, for the convenient discharge of contents from the box. The friction-sealing flaps 49 and 50 bear outwardly against the inside surfaces of the side walls of the cover part 40, and effectively assist in sealing the box when the cover part is in closed position.

The embodiment illustrated in Figs. 15 through 19 possesses characteristics of both of the aforescribed embodiments. The cover part 75 thereof is articulatively connected to the containing part, or box proper, 76, by means of linkage which limits the extent of telescopic sliding movement of the cover part relative to the box proper. The cover part is not entirely removable from the box proper, as in the case of the last described embodiment, but is only partially so. A pouring aperture, similar to the pouring aperture 71 of the last described embodiment, is thus formed at only one side of the cover part. The other side of the cover part is always telescopically associated with the box proper, as in the first described embodiment of Figs. 1 through 8.

The cover part 75 is formed from the cut and scored blank of Fig. 18, and the box proper 76, as well as the articulative linkage, is formed from the cut and scored blank of Fig. 19.

The blank of Fig. 19 is quite different from the previously described corresponding blanks of Figs. 7 and 14. It comprises front and rear wall

panels 77 and 78, respectively, and an interconnecting linkage portion 79. Such linkage portion comprises the common linkage panel section 79a, and the sets of bellows-forming linkage panel sections 79b, 79c and 79d, 79e, respectively, defined by mutually parallel score lines. Locking flaps 79f and 79g extend from opposite ends of the common linkage panel section 79a for a purpose explained hereinafter. The front wall panel 77, the linkage portion 79, and the rear wall panel 78 are serially aligned in that order. Side wall panels 80 and 81 extend laterally from opposite sides, respectively, of front wall panel 77, and similar side wall panels 82 and 83 extend laterally from opposite sides of rear wall panel 78. Friction-sealing flaps 84 and 85 extend from those ends of side wall panels 82 and 83, respectively, which are adjacent the linkage portion 79. Bottom closure flaps 86 and 87 extend oppositely from the ends of front and rear wall panels 77 and 78, respectively, and closure supporting flaps 88 and 89 extend from those ends of side wall panels 80 and 81, respectively, which are adjacent the closure flap 86. The closure flaps 86 and 87 and closure supporting flaps 88 and 89 are, together, adapted to form the glued type bottom closure 90, Fig. 15. The various wall panels, linkage sections, tabs, and flaps are defined in the blank by suitable score lines, as indicated.

The blank of Fig. 18 comprises a top wall panel 92, and front and rear wall panels 93 and 94, respectively, having their outside edges cut on the bias, as illustrated. Extending from the ends of the top wall panel 92 are the sets of side wall panel sections 95, 96 and 97, 98, respectively, of which the sections 96 and 98 are cut short and function as locking flaps as hereinafter explained. Extending from opposite ends of the side wall panel 93 are inter-leaving corner flaps 99 and 100, respectively, and extending from opposite ends of the sidewall panel 94 are inter-leaving corner flaps 101 and 102, respectively, such flaps being cut, as indicated at 103, for accommodating the thickness of the sheet material when assembled.

As before stated, the blank of Fig. 18 forms the cover part 75, and the blank of Fig. 19 forms the containing part, or box proper, 76, as well as the articulative linkage 79. The two blanks are individually folded and glued to form the respective parts.

With respect to the box proper 76, it should be noted that the linkage extends continuously from the upper end of the front wall panel 77 to the upper end of the rear wall panel 78, and, in effect, forms a bridge over the mouth of the box proper, to which bridge the cover part is secured. It should be noted, also, with respect to this particular embodiment, that the blank, Fig. 19, of the box proper provides two sets of side wall panels 80, 81 and 82, 83 which, in forming the box, are glued in fully overlapping relationship, the panels 80, 81 overlying the panels 82, 83, thus forming double thick side walls of the box proper. The friction-sealing flaps 84, 85, extending from panels 82, 83, are folded downwardly over the upper edges of panels 80, 81.

Securement of the cover part 75 to the box proper 76, is accomplished by cooperative association of the locking flaps 79f and 79g of the articulative linkage 79 with the short side wall panel sections, or locking flaps, 96 and 98, respectively, of the cover part. As may be seen in Fig. 17, the locking flaps 96 and 98, when folded inwardly and glued against the inside faces of

their respectively associated inter-leaving corner flaps 99, 101 and 100, 102 serve to engage the locking flaps 79f and 79g of the articulative linkage in edge-to-edge abutting relationship and thus to secure the cover part to the box proper, when the two parts are brought together.

The bias-cut outside edges of front and rear wall panels 93 and 94, respectively, give greater depth to one side of the cover part 75 than to the other, and, accordingly, when the cover part 75 is telescoped upwardly in an extending movement relative to the box proper 76, only one side thereof is removed from the box proper. Only one pouring aperture, see 104, Fig. 16, therefore, is provided between the cover part and the mouth of the box proper, the opposite side of the cover part remaining in engagement with the box proper.

As in the first described embodiment, it is desired that grasping of the cover part for the opening and closing telescopic movement thereof be facilitated. Accordingly, arcuately defined apertures 105 and 106 are provided in the blank of Fig. 18 at the junctions of the front wall panel 93 and the top wall panel 92, and of the rear wall panel 94 and the top wall panel 92, respectively.

The embodiments of the remaining figures of the drawings exemplify the inventive concept as applied to cover parts which are removable from the containing parts or boxes proper, but hinged thereto so that they may be swung back away from the open mouths of the containing parts, or boxes proper. The articulative linkage in each of these instances provides the hinge action, and enables the cover part to be swung back free and clear of the mouth of the containing part, or box proper, within limits depending upon the length of the articulative linkage. The advantageous characteristics of the previously described embodiments are inherent in the embodiments presently considered.

The embodiment illustrated in Figs. 20 through 26 comprises a cover part, or so-called "captive cap," 110, and a containing part, or box proper, 111.

The cover part 110 and the box proper 111 are formed individually from respective suitably cut and scored blanks. The blank of Figs. 25 is used to form the cover part, while the blank of Fig. 26 is used to form the box proper.

The blank of Fig. 26 comprises front and rear wall panels 112 and 113, respectively, side wall panels 114 and 115, respectively, and a conventional lateral glue lap 116, all interconnected in edge-to-edge serial alignment and individually defined by suitable score lines. Bottom closure flaps 117 and 118 extend from the lower ends of front and rear wall panels 112 and 113, and bottom closure supporting flaps 119 and 120 extend from the lower ends of side wall panels 114 and 115, respectively. An articulative linkage portion, indicated generally 121, extends from the upper end of rear wall panel 113, and comprises the linkage panel sections 121a, 121b, and 121c. The upper edges of the side wall panels 114 and 115 may be cut away as indicated at 114a and 115a, respectively and the score line 113a, between the rear wall panel 113 and the linkage panel 121c may be dropped correspondingly from its normal location, to accommodate the linkage material when the cover part is closed over the open mouth of the containing part of the ultimately formed box.

The blank of Fig. 25 comprises front and rear wall panels 122 and 123, respectively, side wall

panels 124 and 125 respectively, and a conventional lateral glue lap 126, all interconnected in edge-to-edge serial alignment and individually defined by suitable score lines, as in the case of the blank of Fig. 26. Top closure flaps 127 and 128 extend from the upper ends of front and rear wall panels 122 and 123, respectively, and inter-leaving closure-supporting flaps 129 and 130 extend from the upper ends of side wall panels 124 and 125, respectively. Corresponding lateral edges of the respective closure-supporting flaps 129 and 130 are cut away, as at 129a and 130a, to accommodate the thickness of the sheet material of the articulative linkage when the two parts of the box are assembled.

The two blanks are individually folded and glued in conventional manner, the bottom closure flaps 117 and 118, and closure-supporting flaps 119 and 120, of the blank of Fig. 26, together forming the bottom closure 131 of the box proper, and the top closure flaps 127 and 128, and closure supporting flaps 129 and 130, of the blank of Fig. 25, together forming the closed top of the cover part 110.

In the assembling operation, the cover part formed by the blank of Fig. 25 is telescoped, in open condition, over the upper end of the box proper formed by the blank of Fig. 26, and the closure-supporting flaps 129 and 130 are folded down against the bellows-like hinge member 132, Fig. 23, formed by suitably folding the lower linkage panel sections 121b and 121c. Thereupon, the upper linkage panel section 121a is folded down over the folded closure-supporting flaps 129 and 130, and, thereafter, the top closure flaps 128 and 127 are folded down and glued, preferably in that order, over the linkage panel section 121a. Thus, the upper linkage panel section 121a of the articulative linkage 121 is inter-leaved between the closure-supporting flaps 129 and 130 and the closure flaps 127 and 128 of the cover part 110, thereby securing such cover part to the box proper 111.

Upon removing the so-formed cover part 110 from the box proper 111 by an upward sliding movement, the bellows-like hinge member serves to prevent loss or misplacement of the cover part, and also enables the cover part to be swung away from the open mouth of the box proper, see 50 particularly Figs. 21, 22, and 24.

It should be noted that the bellows-like hinge member 132 seats within and is accommodated by the indentures 114a and 115a, see Figs. 22 and 26, of the box proper, and, therefore, does not interfere with the proper seating of the cover part on the box proper. So that the bellows-like hinge part 132 will not offer spring-like resistance to the seating of the cover part into closed position, the line of fold between the linkage panel sections 121b and 121c is preferably weakened by perforation, see 133.

In the above described embodiment, it is possible to eliminate the closure flap 128 from the cover blank of Fig. 25, and to utilize the upper linkage panel section 121a of the blank of Fig. 26 in place thereof. In this circumstance, the closure flap 127 would be glued directly to the upper linkage panel section 121a in forming the top closure of the cover part 110.

In the embodiment illustrated in Figs. 27, 28, and 29, the manner of securing of the articulative linkage to the cover part is different from that of the embodiment of Figs. 20 through 26. Pursuant to this embodiment, the cover part 140 is formed with double front and rear walls, while

the containing part, or box proper, 141 is constructed as in the previous embodiment except for the articulative linkage portion, indicated generally 142, Fig. 29, which is provided with locking tabs, 142a', 143a', for cooperation with the inner walls of the cover part 140 in securing such cover part to the containing part, or box proper.

The cover part 140 is formed from the blank of Fig. 28, while the box proper 141 is formed from the blank of Fig. 29, such latter blank being similar to the blank of Fig. 26 in every respect except for certain characteristics of the articulative linkage portion.

The blank of Fig. 28 is generally similar to the blank of Fig. 13, and comprises a substantially centrally located top wall panel 143, from the edges of which extend other wall panel sections, including the panel sections 144 and 145, which together form the front wall of the cover part, and the thereto oppositely extending panel sections 146 and 147, which together form the rear wall of the cover part. Such other wall panel sections also include the panel sections 148 and 149, which together form one of the side walls of the cover part, and the thereto oppositely extending panel sections 150 and 151, which together form the other of the side walls of the cover part. The panel sections 149 and 151 are shorter than their respectively associated panel sections 148 and 150, for providing lock-engaging edges utilized in securing the cover part to the articulative linkage portion of the box. For tying the several thus formed walls together, interleaving corner flaps 152 and 153 extend from opposite ends of the front wall panel section 144 and similar flaps 154 and 155 extend from opposite ends of the rear wall panel section 146. Such flaps may be reduced in width by edge cuts, as at 156, to compensate for the thickness of the sheet material in forming the side walls.

The blank of Fig. 28 is folded and glued to form the cover part 140, the panel sections 149 and 151 being first folded inwardly and glued against the inner faces of their respectively associated panel sections 148 and 150 for providing the lock-engaging edges 157 and 158, Fig. 27.

The articulative linkage portion of the blank of Fig. 29 comprises the upper linkage panel section 142a, and the set of bellows-forming linkage panel sections 142b and 142c. Locking tabs 142a' and 142a'', utilized in securing the upper panel section 142a to the cover part of the box, are formed by cut-lines suitably placed adjacent the normal score line which divides the upper linkage panel section 142a from the linkage panel section 142b.

In assembling the cover part 140 and the box proper 141, the articulative linkage panel 142a is inserted into the open mouth of the cover part, and its longitudinal free edge is lodged over the lock-engaging edge 158 of the inner wall panel 145 of the cover part. The linkage panel 142a is then pressed into face-to-face engagement with the inner side of the top wall panel 143 of the cover part, thus causing the locking tabs 142a', 142a'' to snap over the lock-engaging edge 157 of the inner wall panel 147 of the cover part to thereby lock the cover part 140 securely to the linkage portion of the box.

In the embodiment of Fig. 30, the cover part 160 is single-walled and may be formed by a blank similar to that of Fig. 28, the wall panel sections 145, 147 and 149, 151, however, being eliminated. Such cover part is secured to the con-

taining part, or box proper, 161 by means of articulative linkage 162, whose upper linkage panel section 162a is merely glued to the inner face of the top wall panel of the cover part 160.

All of the described embodiments are right-angled, that is, have rectangular horizontal cross-sections. Such is the preferred and usual box construction. Application of the novel concepts here disclosed, however, are not limited to such constructions, for boxes pursuant to the invention may have a variety of polygonal horizontal cross-sections.

Whereas the invention is here illustrated and described with respect to certain specific embodiments thereof, it should be realized that many changes may be made in these several specific embodiments, and that many other specific embodiments may be constructed, by those skilled in the art, without departing from the spirit and generic concepts of the invention as here set forth and as defined in the following claims.

I claim:

1. A box formed of sheet material and comprising a containing part, a cover part, and articulative linkage interconnecting the said parts, said containing part having lateral panel walls defining a mouth, said articulative linkage comprising a linkage panel member secured to one of said lateral panel walls and comprising panel sections articulatively joined and adapted to fold upon one another substantially bellows-wise, said cover part being of box formation having lateral panel walls corresponding to the said lateral panel walls of the containing part, and having, further, a closed end and an open end, and being adapted for telescopic movement over the mouth-end of said containing part for closing the box, said articulative linkage being secured within and substantially at the closed end of said cover part, having length sufficient to allow removal of said cover part from said containing part, and being arranged to function as a hinge affording swinging movement of said cover part away from the mouth of said containing part when said cover part is removed from said containing part.

2. A box as recited in claim 1 wherein the linkage panel member is articulatively secured to the containing part along a line which is within said containing part and below the level of the mouth thereof, so that the cover part will fit snugly over said containing part when in closed position.

3. A folding box formed of foldable sheet material and comprising a containing part, a cover part, and articulative linkage interconnecting the said parts, the said containing part and the said articulative linkage being formed from a single blank of foldable sheet material cut and scored to provide lateral panel walls defining an open mouth at one end of the containing part and a linkage panel member extending from one of said lateral panel walls at said open mouth, said linkage panel member being traversed across its width by spaced parallel score lines, providing panel sections articulatively joined and adapted to fold upon one another substantially bellows-wise, and said cover part being formed from a single blank of foldable sheet material cut and scored to provide lateral panel walls, corresponding to the said lateral panel walls of the containing part, and closure flaps and closure supporting flaps for closing one end of said cover part, the said cover part being arranged for telescopic movement

over and from the said mouth-end of the containing part, and the free-end panel section of said linkage panel member being interleaved between said closure supporting flaps and said closure flaps of the cover part, thus securing the cover part to the containing part.

4. A folding box formed of foldable sheet material and comprising a containing part, a cover part, and articulative linkage interconnecting the said parts, the said containing part and the said articulative linkage and portions of the cover part being formed from a single blank of foldable sheet material cut and scored to provide lateral panel walls defining an open mouth at one end of the containing part, a pair of linkage panel members extending, respectively, from opposite lateral panel walls at said open mouth, and a pair of closure flaps extending, respectively, from the ends of said linkage panel members, each of the linkage panel members of said pair of same being traversed across its width by spaced parallel score lines, providing panel sections articulatively joined and adapted to fold upon one another substantially bellows-wise, and the remaining portions of said cover part being formed from a single blank of foldable sheet material cut and scored to provide lateral panel walls corresponding to the said lateral panel walls of the containing part, and closure supporting flaps for cooperation with the said pair of closure flaps in the closing of one end of said cover part, the said closure supporting flaps being interleaved between the said linkage panel members and the said closure flaps for securing that portion of the cover part which is formed by the second-named single blank to the said containing part, the said cover part being arranged for telescopic movement over the mouth-end of the said containing part.

5. A folding box formed of foldable sheet material and comprising a containing part, a cover part, and articulative linkage interconnecting the said parts, the said containing part and the said articulative linkage and portions of the cover part being formed from a single blank of foldable sheet material cut and scored to provide lateral panel walls defining an open mouth at one end of the containing part, a pair of linkage panel members extending, respectively, from opposite lateral panel walls at said open mouth, and a pair of closure flaps extending, respectively, from the ends of said linkage panel members, each of the linkage panel members of said pair of same being traversed across its width by spaced parallel score lines, providing panel sections articulatively joined and adapted to fold upon one another substantially bellows-wise, and the remaining portions of said cover part being formed from a single blank of foldable sheet material cut and scored to provide lateral panel walls corresponding to the said lateral panel walls of the containing part, friction-sealing flaps for those opposite lateral walls of said cover part which lie between said linkage panel members, and closure supporting flaps for cooperation with the said pair of closure flaps in the closing of one end of said cover part, the said closure supporting flaps being interleaved between the said linkage panel members and the said closure flaps for securing that portion of the cover part which is formed by the second-named single blank to the said containing part, the said cover part being arranged for telescopic movement over the mouth-end of the said containing part.

6. A box formed of sheet material and comprising a containing part, a cover part, and articulative linkage interconnecting the said parts, said containing part having lateral panel walls defining a mouth, said articulative linkage comprising a pair of linkage panel members respectively secured to two of those said lateral panel walls which are disposed opposite each other, and each of said linkage panel members comprising panel sections articulatively joined and adapted to fold upon one another substantially bellows-wise, and said cover part being of box formation having lateral panel walls corresponding to the said lateral panel walls of the containing part, and having, further, a closed end and an open end, and being adapted for telescopic movement over the mouth-end of said containing part and sealing members carried by one of said box parts for effecting a relatively tight fit between the cover part and the containing part when the cover part is in place over the mouth of the containing part.

7. A box formed of sheet material and comprising a containing part, a cover part, and articulative linkage interconnecting the said parts, said containing part having lateral panel walls defining a mouth, said articulative linkage comprising a pair of linkage panel members respectively secured to two of those said lateral panel walls which are disposed opposite each other, and each of said linkage panel members comprising panel sections articulatively joined and adapted to fold upon one another substantially bellows-wise, and said cover part being of box formation having lateral panel walls corresponding to the said lateral panel walls of the containing part, and having, further, a closed end and an open end, and being adapted for telescopic movement above the mouth-end of said containing part, the articulative linkage having a length to afford extended telescopic movement of the cover part relative to the containing part to provide a clearance between the cover part and the containing part to afford a dispensing opening therebetween.

8. A box formed of sheet material and comprising a containing part, a cover part, and articulative linkage interconnecting the said parts, said containing part having lateral panel walls defining a mouth, said articulative linkage comprising a pair of linkage panel members respectively secured to two of those said lateral panel walls which are disposed opposite each other, and each of said linkage panel members comprising panel sections articulatively joined and adapted to fold upon one another substantially bellows-wise, and said cover part being of box formation having lateral panel walls corresponding to the said lateral panel walls of the containing part, and having, further, a closed end and an open end, and being adapted for telescopic movement over the mouth-end of said containing part, said articulative linkage being of a length to afford only limited sliding movement of the cover part partially above the mouth end of the containing part, one of the lateral walls of the cover part which is disposed between the pair of articulative linkage panel members being formed to provide with the mouth end of the containing part a pouring aperture which is located to be closed by the cover part when the cover part is in retracted telescopic position over the containing part and to be opened when the cover part is in extended telescopic position over the containing part.

9. A box as recited in claim 1 wherein the cover part comprises extensions of its wall panels which are disposed interiorly of the cover part in mutually superposed relation and an end panel section of the articulative linkage is secured 5 interiorly of the cover part by interleaving said end panel section between said mutually superposed extensions of the cover part.

10. A box as recited in claim 1 wherein the cover part comprising extensions of its wall 10

panels which are disposed interiorly of the cover part in mutually superposed relation at the inner face of the closed end of the cover part and an end panel section of the articulative linkage is secured 5 interiorly of the cover part adjacent the closed end of the cover part by interleaving the end panel section between the mutually superposed extensions of the cover part.

MARSHALL I. WILLIAMSON.
